(57) **CLAIM**

The ornamental design for an arcade game, as shown and described.

DESCRIPTION

FIG. 1 is a perspective view of an arcade game showing my new design;

FIG. 2 is a front elevational view thereof;

FIG. 3 is a back end elevational view thereof;

FIG. 4 is a right elevational view thereof;

FIG. 5 is a left elevational view thereof;

FIG. 6 is a top plan view thereof; and,

FIG. 7 is a bottom plan view thereof.

The broken lines in the drawings depict portions of the arcade game that form no part of the claimed design.
